HEADREST COVER UNIT FOR DENTAL CHAIRS

Irving E. Rotner, Spring Valley, N. Y.

Application April 8, 1950, Serial No. 154,765

3 Claims. (Cl. 155—176)

1

This invention relates to improvements in head rest cover units for dental chairs, etc., of the pad of separable sheets type shown in my U. S. Patent No. 2,068,571, dated January 19, 1937.

Its principal object is to provide a separable sheet cover unit for head rests of dental, barber chairs, etc., which will always lie flat and undistorted against the head rest.

Its principal feature of construction over my said U. S. Patent No. 2,068,571 resides in the backing portion of the unit, whereby buckling of the separable sheets is avoided.

Other objects of the invention will be apparent from the following description and drawing, which describes and illustrates a preferred practical embodiment of the invention.

In the drawing:

Fig. 1 is a rear perspective view of a pair of head rests of a dental chair, with the improved pad unit mounted thereon;

Fig. 2 is a sectional view on the line 2—2 of Fig. 1;

Fig. 3 is a plan view of the back of the pad unit;

Fig. 4 is a plan view of the front of the unit;

Fig. 5 is a sectional view on the line 5—5 of Fig. 3; and,

Fig. 6 is a plan view of the back of a single section pad unit.

Referring to the drawing, the base of the unit consists of a flexible backing 10 of the configuration shown in Fig. 3. The said backing may be made from rubber, cloth, vinyl film, or any desired flexible material, and is die-cut to present two complementary circular sections 11 and 12, integral with each other along their common connecting arm 13; each said section having a centrally located oval head rest receiving opening 14, and a plurality of spaced and inwardly extending peripheral cut-outs 15. The said cut-out portions 15 are in aligned relationship, and each is of arcuate shape. As shown in Fig. 3, each head rest section 10 and 11 has an upper and lower cut-out and an end cut-out. The upper and lower cut-outs of each section being in vertical alinement and the end cut-out of each section being in horizontal alinement. Backing 10 can be of any desired configuration and size as long as it is divided into two sections, one section being foldable with respect to the adjacent section.

Superposed on backing 10 is the flexible sheet 16, the said sheet being generally of the same configuration as backing 10, save it has no cut-

out portions. Sheet 16 is stitched to backing 10 adjacent their marginal edges by the stitching 17. When so stitched, the sheets 10 and 16 form two pockets or compartments A and B therebetween. Access is had to each said pocket through opening 14, and each said section is adapted to receive a head rest section H therein through said openings.

Sheet 16 is provided with a projecting tab portion 18, the function of which will hereinafter be explained. Said sheet can be made of cloth, rubber, vinyl sheeting or any other desired flexible material. It is die-cut to the configuration shown in Fig. 3, and save for the cut-out portions 14 and 16 of backing sheet 10, it is otherwise identical to said backing sheet 10. Like backing sheet 10, said sheet 16 is divided into two circular sections which are foldable relative to each other along an integral connecting arm.

Superposed on intermediate sheet 16 are a plurality of separable sheets 19 of grease proof and oil-proof paper. The said sheets 19 conform in every respect to the configuration of sheet 16, being also provided with a projecting tab portion 20 overlying tab portion 18 of said sheet 16.

Sheets 19 are held in superposed assembled relation as a pad unit, with backing sheet 10 and intermediate sheet 16 by a plurality of staples 21 passing through said sheets 19 and said intermediate sheet 16. Such connection can be by staple, hand loops or by stitching by machine. It will be noted from Fig. 3 that each staple 21 is located in each cut-out portion 15 of backing sheet 10. The topmost sheet 19 of the pad unit can be removed after usage to present a clean sheet 19 when desired. This is accomplished by pulling tab 20 of each sheet 19 upwardly and then tearing the sheet from staples 21.

Figs. 1 and 2 show the pad unit mounted on the head rests H. Each opening 14 is of sufficient dimension so as to permit the insertion of each head rest H therethrough, so as to be held in each respective pocket or compartment A and B. It will be noted that cut-out portions 15 communicate with each said pocket.

It will be observed from Figs. 1 and 2 that head rests H are disposed in angular relation to each other. Consequently, when the pad unit is mounted on said head rests, the two sections of the unit will likewise assume an angular position, as the said sections are readily foldable with respect to each other along their integral connecting arm.

Each section of the pad unit will lie flat against

its respective head rest H, and the presented sheets 19 thereof will not be bent or distorted. There is no tension on the said sheets, by reason of the improved backing construction. This is strikingly illustrated in Fig. 1 wherein it will be discerned that the tension and pull is confined to backing sheet 10 and its associated sheet 16. The provision of the spaced peripheral cut-outs 15 enables portions of said backing sheet 10 to pull away from its associated sheet 16. The buckling and distortion are thus confined to the backing section. The points of greatest stress or pull are at the staple points 21, wholly located in each cut-out 15.

Fig. 6 shows a single section pad unit, which can be slipped over each head rest H individually. The backing of this unit is provided with four cut-outs, otherwise this embodiment is identical to the construction heretofore described, save that the connecting arm has been omitted.

There has been illustrated and described a preferred embodiment of the invention. It is not desired to be limited to any specific configuration or size or material. If desired, intermediate sheet 16 may be dispensed with.

What is claimed is:

1. A pad unit for a sectional headrest comprising a backing sheet, an intermediate sheet and a plurality of separable sheets, all said sheets being cut to present two complementary sections integral with an intermediate arm, all said sheets being foldable along said intermediate arm, the backing sheet having a centrally located headrest receiving opening formed in each section thereof and also having a plurality of marginal cut-outs formed in each said section, the intermediate sheet being superposed on said backing sheet and being stitched thereto adjacent the marginal edges of said sheets to form a pair of compartments therebetween, each of said compartments

being adapted to receive and hold therein a headrest, the plurality of separable sheets being superposed on said intermediate sheet and being detachably secured thereto adjacent the marginal cut-outs, the tension being on said intermediate and backing sheets when the unit is mounted on the headrest.

2. A pad unit for a sectional head rest in accordance with claim 1, in which each section of the backing sheet is provided with three marginal cut-outs, an upper and lower cut-out and an end cut-out, the upper and lower cut-outs of each section being in vertical alinement, and the end cut-out of each section being in vertical alinement with each other.

3. A pad unit for a sectional headrest comprising a backing section having two laminae, one of said laminae having an opening therein to receive a headrest and also having a plurality of marginal cut-outs formed therein, a plurality of separable sheets superposed and detachably secured to the other of the said laminae adjacent the said marginal cut-outs, the tension being on the said backing section when the unit is mounted on the headrest.
